OUTSIDE MOUNTED AIR CONDITIONING
UNITWilliam F. Borgerd, Evansville, Ind., assignor to
International Harvester Company, a corpora-
tion of New Jersey

Application May 5, 1951, Serial No. 224,782

8 Claims. (Cl. 62—129)

1

This invention relates generally to an air conditioning unit and more particularly to an air conditioning unit mounted outside a room above a window.

One popular design of a room air conditioner which has been developed is the window type unit which fits in the lower portion of a window and is secured to the window sill. Another popular design is the console type unit which is disposed within a room adjacent a window with a cabinet which rests upon the room floor. Both types have proved unsatisfactory because of the cramped construction thereof which reduces cooling effectiveness and causes field service to be more costly and more frequently needed. Most users object to keeping the window type unit in place during the winter months because it obstructs a considerable portion of the window and leaks cold into the room. For these reasons the unit is usually removed in the fall and replaced in the spring, thus adding the expense for such removal to the operating cost of the unit. The console model is objectionable because of the floor space it requires, because it occasionally drips condensate onto the floor, and because the noise of the running machinery therein cannot be satisfactorily insulated from the room. However, the console model is usually left in place during the winter months since removal thereof is made difficult by the weight and bulk of the unit. The present invention provides an air conditioning unit which overcomes the above mentioned disadvantages of the window type and console type units.

One object of the invention is to provide an air conditioning unit which is secured to an exterior portion of a wall with an air passageway of minimum height extending into a room window.

Another object is to provide a room air conditioner having the condenser so located that outside air may be conveniently circulated thereover so as to provide excellent cooling thereof.

Another object is to provide a room air conditioner having a cabinet of such size that the refrigeration system and associated parts may be located therein without overcrowding.

Another object is to provide a window mounted air conditioner which may be completely serviced from outside the room being conditioned.

Another object is to provide a room air conditioner so located that a minimum amount of operating noise from the refrigeration system and air circulating fans will be projected into the room being conditioned.

2

Another object is to provide a window mounted air conditioner with means for effectively removing evaporator condensate therefrom without the necessity of plumbing equipment.

Another object is to provide a room air conditioner with damper means for circulating outside air into the room being conditioned.

Another object is to provide a window mounted air conditioning unit so positioned in relation to the window that the window sash may be completely closed without removing any part of the unit.

Another object is to provide a splitter bar which will direct warm room air from the lower portion of the room into the air conditioner cabinet and which will direct cooled air from the cabinet into the upper portion of the room.

Another object is to provide a splitter bar which is pivotally secured within the room so that it can be rotated from operating position to allow complete closing of the window.

Another object is to provide an air conditioner mounted on the exterior wall of a room above a window with an elbow section projecting into the top portion of the window which provides communication between the room and cabinet.

Another object is to provide an air conditioner which is located above a window so that it shields the window and reduces heat entrance into the room in the same manner as a window awning.

Further objects and advantages of the invention will become apparent as the following description proceeds, and the features of novelty which characterize the invention will be pointed out with particularity in the claims annexed to and forming a part of this specification. For a better understanding of the invention, reference may be had to the accompanying drawings in which:

Figure 1 is a sectional view of an air conditioning unit taken along line 1—1 of Figure 2.

Figure 2 is a sectional view taken along line 2—2 of Figure 1 with portions broken away.

Figure 3 is an elevational view of the upper portion of the inner window casing showing the louvers and splitter bar.

Figure 4 is a sectional view taken along line 4—4 of Figure 1.

Figure 5 is a perspective view of the air conditioning unit.

Referring particularly to the drawings, the air conditioning unit 10 is shown mounted above a window 11 on the exterior portion of a room wall 12. The window 11 comprises generally a sash 13 and pane 14 mounted within a window casement

15. The unit is provided with a frame 16, shown in part, and an outer casing 17 comprising vertical end walls 18 and 19, front wall 20 and a top wall 21 having a portion which slopes downwardly toward the front wall. The unit is positioned adjacent room wall 12 with bolts 22 extending through frame 16 and fastened in the wall in order to secure the unit above the window. Resilient pads 23 are positioned between the room wall 12 and the unit 10 in order to isolate vibration.

The space enclosed by casing 17 is divided into a high side compartment 24 and low side compartment 25 by an insulated partition 26 which comprises spaced apart wall members 27 and 28 with insulating material 29 therebetween. The partition 26 is provided with a front wall 30, end walls 31 and 32, back wall 33, and bottom wall 34 which enclose and insulate compartment 25. A lid 35 is secured to back wall 33 by hinges 43 and is adapted to close the top of compartment 25. Back wall 33 is provided with a duct or elbow section 36 comprising top wall 37, bottom wall 38 and side walls 39 and 40. The duct 36 extends into the window 11 and terminates adjacent window sash 13 in slightly spaced relationship thereto. A gasket 41 is secured to the duct in order to seal between the sash and the duct. The end of duct 36 adjacent to the window 11 is open so that air may be circulated from the room into low side compartment 25 when the sash 13 is lowered.

An opening 42 is provided in the bottom wall 44 of high side compartment 24 and a condenser 45 is positioned over this opening. Secured to partition wall 27 is a bracket member 46 to which an electric motor 47 is fastened. The motor shaft 48 carries a fan 49 which pulls outside air up through the condenser 45 and discharges it through an opening 50 provided in the top wall 21 of casing 17. Removably secured in opening 50 is a screen 51 which will prevent foreign matter from falling into the compartment 24. Secured to bottom wall 44 adjacent condenser 45 is a motor-compressor unit 52 which will be cooled by the air circulated by fan 49. Casing 17 is removably attached to frame 16 so that it may be removed for servicing of the high side members.

The low side compartment 25 and elbow section 36 are divided into an intake passageway 53 and outlet passageway 54 by a dividing wall 55. The outer edge 56 of the wall 55 is spaced from the front wall 39 of partition 56 in order to provide a connection between the passageways. Positioned adjacent edge 56 in outlet passageway 54 is an evaporator 57 which extends across the width of the passageway. Positioned under the evaporator 57 is a trough or tray 58 to which a tube 60 is connected. The tube 60 extends through front wall 30 of the partition 26 and slopes downwardly with the lower end 61 positioned slightly above condenser 45. As is well known in the art, water from the air being cooled will condense on the cold surfaces of an evaporator. In the illustrated embodiment, any water condensed on evaporator 57 will drip into tray 58 from which it will drain through tube 60 onto the condenser 45. As the water spreads over the surface of the condenser 45, it will absorb heat therefrom and be vaporized, then picked up by the air stream of fan 49 and discharged through opening 50. If the water is not entirely vaporized by the condenser 45, it will drip harmlessly to the ground surface therebelow. In this manner the condensate is effectively removed and is also utilized in cooling of the condenser 45.

Positioned across inlet passageway 53 is a filter element 62 which will clean the air of any objectionable foreign matter. Two spaced apart blowers 63 and 64 are secured in outlet passageway 54 with an electric motor 65 having a double end shaft 66 for driving the blowers. The motor 65 is positioned between the blowers and the base 67 thereof is secured to back wall 33 of the partition 26. Enclosed by blower casings 68 and 69 are rotors 70 and 71 respectively which are mounted on shaft 66 and are supplied with fan blades for pulling air through a circular air inlet opening 72 provided in an end wall of each casing. The blowers 63 and 64 discharge into a common outlet 73 having top wall 74, back wall 75, bottom wall 76, and side walls 77 and 78 which flare outwardly to meet the side walls 39 and 40 respectively of elbow section 36. Louvers 79 are removably secured to side walls 39 and 40 of elbow section 36 in outlet passageway 54. Also removably secured to these side walls 39 and 40 in inlet passageway 53 are louvers 80. A rectangular shaped opening 81 is provided in the bottom wall 34 of partition 26 in which a damper 82 is pivotally secured by pins 83 and 84. A handle 85 is attached to the damper 82 which may be reached from within the room by removing louvers 80 and reaching into inlet passageway 53.

Positioned on the inside of the room is a splitter bar 86 having pins 87 and 88 which are pivotally secured within brackets 89 and 90 fastened to window casement 15. When in operating position, as shown in full lines in Figure 1, the inner edge 91 of the splitter bar 86 is adjacent dividing wall 55 and rests upon pins 92 and 93 which are fixedly secured to the window casement 15. In this position the splitter bar acts as a continuation of the dividing wall 55 and aids in dividing and directing the air stream flowing between the room and unit 10. The lower surface 94 of the splitter bar 86 is curved downwardly in order to direct air from the lower portion of the room into inlet passageway 53. The upper surface 95 of the bar 86 is curved upwardly so that the air discharging from the outlet passageway 54 will be directed into the upper portion of the room from where it will drop downwardly across the entire room. If sash 13 is to be raised, splitter bar 86 is rotated to the position shown by dotted lines in Figure 1 so that the sash may be closed without the removal of any part of the air conditioning unit 10.

The refrigeration system will be charged with a suitable refrigerant which will be compressed by motor-compressor unit 52 and passed through tube 96 to condenser 45 where it will be cooled by the outside air being passed over the condenser by fan 49. The refrigerant is conveyed from condenser 45 by capillary tube 97 to evaporator 57 where it will extract heat from the room air being circulated over the evaporator 57 by way of passageways 53 and 54. The refrigerant is then returned to the motor-compressor unit 52 by tube 98 to complete the refrigeration cycle.

The air conditioning unit 10 can be completely assembled by the manufacturers and then shipped to the proper location where it can be easily and quickly secured to the wall 12 by bolts 22. After proper electrical connections are made and sash 13 opened, the unit is ready for operation. It is contemplated that suitable controls (not shown) be mounted within the room in any easy to reach location. With damper 82 in closed position as shown in solid lines in Fig-

ure 1, blowers 63 and 64 will draw air into inlet passageway 53 from the lower portions of the room, circulate it through filter 62 and evaporator 57 and then discharge it through outlet passageway 54 into the upper portion of the room. Any water which condenses upon the evaporator 57 will drip into tray 58 and be drained onto condenser 45 by tube 60 where it will be vaporized and passed out outlet opening 50. The condenser 45 and motor-compressor unit 52 will be properly cooled by outside air circulated by fan 49. The high side members will be cooled even when the fan 49 is not operating by natural air movements through the chimney shaped condenser compartment 24. Even distribution of the cooled air within the room will result from the manner in which the air streams are directed by splitter bar 86. Top curved surface 95 will direct the cold air from outlet passageway 54 into the upper portion of the room near the ceiling from where it will drop to lower portions of the room, thus setting up natural convectional air currents across the room to insure uniform cool air delivery with a minimum amount of objectionable drafts.

By opening damper 82 to the position shown by dotted lines in Figure 1 and operating only motor 65, fresh air will be filtered and circulated into the room. By partially opening the damper 82, with the refrigeration system and motor 65 operating, the air being cooled will be a mixture of return room air and fresh air and the percentage of each can be controlled by properly setting the damper.

Splitter bar 86 will direct the air entering and leaving the room in the manner explained heretofore and will also blend in neatly with the window casement 17. Louvers 79 and 80 will also aid in producing proper air circulation and may be made adjustable if desired. Window sash 13 may be raised and the window completely closed by merely rotating splitter bar 86 to the position shown by dotted lines in Figure 1. This is a distinct advantage over the usual type of window air conditioner which must be removed before the window is closed. With the unit 10 located above the window 11 as illustrated, it will shield the window and reduce heat entrance into the room in the same manner as a window awning. By constructing the outer casing 17 to have the appearance of an awning, the unit will present a neat appearance when attached to a home. The elbow section 36 has a height of only a few inches so that it obstructs only a small portion of the window 11.

Servicing the unit 10 can be completed from outside the house without the necessity of entering the room. By removing casing 17, access to all parts of the high side compartment 24 is provided. Means for locking the casing 17 to the frame 16 (not shown) may be provided to prevent unauthorized removal or tampering of the unit. With casing 17 removed, lid 35 can be opened in order to provide entrance into the low side compartment 25. Filter 62 may be reached by removing louvers 80 and reaching through inlet passageway 53, or by opening damper 82 and reaching through opening 81.

Although the unit 10 has been shown in connection with a double hung window, it will be apparent that it is adaptable for use with other types of windows. From the foregoing disclosure it is seen that a simple and compact construction is provided which is economical in

manufacture and maintenance. The unit is located in relationship to a window so that it protects the window, rather than obstructing it, with all parts located on the exterior wall of the room so that all parts are properly cooled and the noise from the running machinery is insulated from the room. The air and noise from the high side compartment are discharged upwardly so that they will not be projected onto a neighboring building.

It should be understood that changes and modifications in the form, construction, arrangement and combination of parts may be made and substituted for those herein shown and described without departing from the spirit of the invention as set forth in the appended claims.

What is claimed is:

1. The combination of an air conditioning unit comprising a casing positioned outside a room above a window; a duct which projects into said window and terminates adjacent a sash so that the sash can be opened and closed; means for drawing room air through said duct into said casing, cooling the air and returning it to the room through said duct; and a splitter bar positioned in front of said duct in order to direct warm air from the lower portion of the room into the duct and cold air from the duct into the upper portion of the room.
2. The combination of an air conditioning unit comprising a cabinet which projects into a window of a room; an opening provided in said cabinet which communicates with said room; means for drawing room air through said opening into said cabinet, cooling the air therein and returning it through said opening to the room; a splitter bar positioned across said window having an upper surface, which directs air leaving said opening toward the ceiling of said room, and a lower surface which directs air from the floor of said room into said opening.
3. The combination of an air conditioning unit having a casing positioned outside a room above a window; a duct which projects into said window and provides communication between said casing and room; means for drawing room air through said duct into said casing, cooling the air therein and returning it through said duct to the room; and a splitter bar pivotally secured within the room so that it can be rotated away from said window when the window is closed; said splitter bar having an upper curved surface which directs air leaving said duct toward the ceiling of the room, and a lower curved surface which directs air from the floor of said room into said duct.
4. The combination of an air conditioning unit comprising a cabinet located outside a room above a window; said cabinet projecting into said window and terminating adjacent a sash of said window so that said sash may be opened and closed; an opening provided in said cabinet which communicates with said room when the sash is opened; means for drawing room air through said opening into said cabinet, cooling the air therein and returning it through said opening to the room; and a splitter bar pivotally secured within said room which cooperates with said opening when the window is open to direct air entering said opening from one portion of the room and air leaving said opening to another portion of the room; said splitter bar adapted to be rotated away from said opening when the window is closed.
5. The combination of an air conditioning unit

comprising a casing having means for securing it to an exterior wall surface of a room above a window; an insulated partition which divides the cabinet into a high side compartment and a low side compartment; a duct which projects into the upper portion of the window and provides communication between said low side compartment and said room; an evaporator positioned in said low side compartment; a condenser and compressor positioned in said high side compartment; means for circulating room air over said evaporator; and a splitter bar pivotally secured within said room for directing warm air from the lower portion of the room into said duct and cold air from the duct into the upper portion of the room. 15

6. The combination of an air conditioning unit comprising a casing having means for securing it to an exterior wall surface of a room above a window; an insulated partition which divides the cabinet into a high side compartment and a low side compartment; a duct which projects into the upper portion of the window and provides communication between said low side compartment and said room; an evaporator positioned in said low side compartment; a condenser and compressor positioned in said high side compartment; means for circulating room air over said evaporator; a splitter bar pivotally secured within said room for directing warm air from the lower portion of the room into said duct and cold air from the duct into the upper portion of the room; and a fresh air damper in said low side compartment for admitting outside air thereinto. 25

7. An air conditioning unit comprising a casing removably secured to an outer wall above a room window; said casing projecting outwardly from the wall so that it shields the window; an insulated partition which divides the casing into a high side compartment and a low side compartment; said high side compartment provided with openings through which outside air is circulated for cooling a condenser and compressor located therein; said low side compartment provided with an evaporator and a duct which extends into the said window; a dividing wall which divides the

6 low side compartment and high side compartment into an inlet passageway and outlet passageway; and a splitter bar which cooperates with said dividing wall to direct air from the room into said inlet passageway and air from the outlet passageway into said room; said splitter bar being rotatively mounted within said room so that it is adapted to be rotated away from said dividing wall to allow closing of the window. 15

8. An air conditioning unit of the character adapted for mounting exteriorly of the window opening of a room, comprising: a casing adapted for mounting on an exterior wall; a longitudinally extending insulated partition that divides the casing into a high side compartment and a low side compartment; a horizontally extending duct that connects with said low side compartment and is adapted to extend into the top portion of a window opening; means, including a substantially horizontally disposed and longitudinally extending partition that extends longitudinally throughout the length of the low side compartment and the horizontal duct connected therewith, for fashioning an inlet passageway and an outlet passageway vertically spaced therefrom that provides communication between said casing and a room to be conditioned; a condenser, compressor and means for circulating air from outside the room thereover disposed in said high side compartment; an evaporator disposed in said low side compartment; and means for circulating air from the room through said inlet passageway, over said evaporator and back into the room through said outlet passageway.

WILLIAM F. BORGERD.
